United States Patent Office

Des. 198,147
Patented May 5, 1964

198,147

COOLING TOWER

Peter M. Phelps, Kentfield, and Alfred L. Fuller, Santa Rosa, Calif., assignors to The Fluor Corporation, Ltd., Los Angeles, Calif., a corporation of California

Filed July 30, 1962, Ser. No. 71,110

Term of patent 14 years

(Cl. D62—4)

The figure illustrates the cooling tower in perspective, and the undisclosed side and end are substantially the same in appearance as the side and end shown.

The dominant features of our design reside in the portions shown in full lines.

We claim:

The ornamental design for a cooling tower, substantially as shown and described.
